UNITED STATES PATENT OFFICE

151,338

DESIGN FOR A CHILD'S DOLL

Helen R. Farnam and Blanche S. Wheeler,
Minneapolis, Minn.

Application May 31, 1947, Serial No. 139,378

Term of patent 14 years

(Cl. D34—4)

To all whom it may concern:

Be it known that we, Helen R. Farnam and Blanche S. Wheeler, citizens of the United States of America and residing in the city of Minneapolis, county of Hennepin, State of Minnesota, have invented a new, original, and ornamental Design for a Child's Doll, of which the following is a specification, reference being had to the accompanying drawing, forming a part thereof, wherein:

Fig. 1 is a front elevation of a child's doll, showing our new design;

Fig. 2 is a side elevation of the same; and
Fig. 3 is a back elevation of the same.

We claim:

The ornamental design for a child's doll, substantially as shown.

HELEN R. FARNAM.
BLANCHE S. WHEELER.
